(57) **CLAIM**

The ornamental design for a vacuum packaging device, as shown and described.

DESCRIPTION

FIG. 1 is a front perspective view of the vacuum packaging device showing the new design;

FIG. 2 is a rear perspective view thereof;

FIG. 3 is a front elevation view thereof;

FIG. 4 is a back elevation view thereof;

FIG. 5 is a top plan view thereof;

FIG. 6 is a bottom plan view thereof;

FIG. 7 is a right side elevation view thereof; and,

FIG. 8 is a left side elevation view thereof.

The broken lines in the drawings are for illustrative purposes only and form no part of the claimed design.
